UNITED STATES PATENT OFFICE.

HERMAN BEHR, OF NEW YORK, N. Y.

ABRASIVE-PAPER-MANUFACTURING MACHINE.

1,357,943.

Specification of Letters Patent.

Patented Nov. 9, 1920.

Application filed November 29, 1919. Serial No. 341,471.

To all whom it may concern:

Be it known that I, HERMAN BEHR, a citizen of the United States, residing in the city, county, and State of New York, have 5 invented certain new and useful Improvements in Abrasive-Paper-Manufacturing Machines, of which the following is a specification.

This invention relates to abrasive-paper-manufacturing machines, but machines embodying this invention may be used for very different purposes. The main object of the invention is to deposit adhesive or other fluid under regulated control, on sheet material during the travel of that material, and with accuracy as to evenness and thickness or thinness of deposit; and this is a very important economic matter for reasons fully set forth in my application Serial No. 20 341,470, filed Nov. 29, 1919. The present machine embodies some of the features set forth in said application, but in a mechanically different manner. Certain features of my invention set forth in said application 25 are not shown in the machine herein described. By "abrasive paper" herein I mean to include any abrasive sheet material that can be manufactured on the present machine, together with any or all other 30 products, whether abrasive or not, that can be made on it. In the production of so-called abrasive paper or the like by means of the present invention, a substantial saving of adhesive is effected with a consequent 35 substantial saving of the abrasive that is deposited on the underlying deposit of adhesive; and successive runs of webs of backing, whether paper, cloth or otherwise, and of abrasive, may be made with the result 40 that repeat orders for a given quality or grade may be filled with exactitude, which is not the case when such abrasive material is made by heretofore-existing means; it being seldom the case that any substantial 45 number of successive sheets of a given grade can be produced subsequently with anything like exactitude in respect to quantity of adhesive and quantity of abrasive; and it is largely due to the relative proportions of the adhesive and of the abrasive 50 on a paper or cloth back of uniform thickness that the quality of a given grade of abrasive material is due.

In the accompanying drawings forming a 55 part hereof,

Figure 1 is a side elevational diagram-

matic view in part, of so much of a known sandpaper manufacturing apparatus as is necessary to be shown in connection with the present invention; and in part, of such 60 apparatus when it embodies features of this invention. The view shows in end elevation looking from a side of the machine, my new gluing apparatus with a web of backing running through it and past means for application of abrasive on the previously-deposited layer of adhesive on the upper surface of the web, the usual pneumatic web-feeding drum being also shown.

Fig. 2 is a front elevation of a machine 65 embodying this invention, showing a web in place.

Fig. 3 is an elevation of the right-hand side of the machine viewed from in front as in Fig. 2, and partially shows the overhead friction-driving mechanism for the 75 machine.

Fig. 4 is a top plan view of the machine and is intended particularly to show the overhead friction-driving mechanism shown 80 in Fig. 3.

Fig. 5 is a vertical central sectional view showing the distributing cross-head shown in Fig. 2, and the rod valves for the exit slit closed.

Fig. 6 is an end view of the distributing 85 cross-head;

Fig. 7 a transverse section thereof at line 7-7 of Fig. 6;

Fig. 8 is an enlarged view showing one of 90 the rod-valve operating cam and spring mechanisms with the drive or main shaft of the machine connecting with the shaft of the web support for rotating the latter;

Fig. 9 is a partial face view of a portion 95 of a web of suitable backing on which separated disk deposits of adhesive or other liquid are shown; and

Fig. 10 is a transverse section at line 10-10 of Fig. 1, showing the nut and 100 threaded piston rod construction.

Referring to that form of the invention shown in the drawings, 1 indicate upstanding side frames of the gluing machine; 2 a transverse roll past which the web W of 105 flexible backing runs upwardly through a transverse slot α through the floor A on which the machine is located; 3 indicates a transverse upper roll for the web which is led over it and forwardly and downwardly under and thence upwardly and rearwardly over a transverse, front web-

2
supporting roll 4 which is the preferable form of work-support, or support for the material to be treated. From roll 4 the web is shown extending rearward over a transverse drum 5 with the upper surface of the web in contact with a transverse wiper 6, the web with its upper surface faced with adhesive running over a transverse supporting roll 7, and thence under means for depositing abrasive on the adhesive on the backing and shown as the usual sander S, and thence over a pneumatic-suction web-feed drum 8 by which the web is continuously pulled from the web-supporting roll 10 rearwardly under the sander, and thence to the festooning mechanism referred to but not shown. In Fig. 1, I show in dotted lines α , the old gluing roll that ran in a glue trough and deposited the glue or matrix on the web as it turned upward over the front, web-supporting roll 4. Said glue-roll α and its trough are now dispensed with and the upper surface of the web W at the upper peripheral crown of the roller 4 has the adhesive deposited on it by a lengthwise-chambered glue-depositing crosshead, parallel to and extending lengthwise of the upper peripheral crown of roll 4.

The gluing machine is shown provided with inward upstanding posts 9 each of which is transversely aligned with an outward upstanding side frame 1. The main shaft of the present machine is indicated by M and has bearings in each frame member 1 and 9. The glue-depositing crosshead is indicated by 10. The shaft M is equipped with a stepped belt pulley 11 for application of power. The glue-depositing crosshead is formed of a lengthwise-split tube 40 the ends of which are exteriorly screw-threaded at 12, each end of the split tube being provided with a screw cap 13 on its threaded end; and the members of the split tube are otherwise held in tubular assembly by arcuate clamps 14 and screws 15 through the arcuate clamps, the free ends of each clamp embracing the upper split tube member and extending downwardly into engagement with upper opposed portions 45 of the under split tube member which is formed at its bottom crown portion with a lengthwise-extending glue-exit preferably in the form of a continuous slit 16 from which the adhesive is pressed out evenly and 50 under regulable pressure upon the upper surface of the web while it is in continuous rearward travel from the front, web-supporting roll 4, and has its upper surface coated with glue from edge to edge or between 55 its edges, according to the adjustment of the lengthwise-aligned, endwise-movable, rod-valves 17 each of which projects into the chamber of the glue-distributing crosshead through a stuffing box 18 with which each 60 cap 13 is provided in its lower portion, the

inward end portion of each rod-valve passing between interior side guides 19 between which the rod-valves work. The guides 19 are fixed to the interior bottom wall of the under split member of the glue-distributing crosshead, and are located adjacent and some at one side and others at the other side of the exit slot 16. The under surface of each rod-valve works in close contact with the inner wall surfaces adjacent the slot 16. 75

The rod valves may be pushed in wholly or partially to close the slot 16; and may be pulled out by hand when desired to open up the exit slot 16 to any desired length, according to the width of the web to be 80 faced with the adhesive or to the width of the adhesive to be deposited on the web.

For obtainment of a determinable thickness of adhesive on the web surface to be treated, and in order to secure uniformity 85 of thickness of the deposited adhesive, the glue-depositing crosshead is, preferably and by one feature of this invention, supplied with adhesive which is under a forced and constant pressure feed that is regulable by 90 means of variable-speed and piston mechanisms whereby, for a given quality of adhesive at a given temperature, with the web traveling at a predetermined speed, and with the controllable forced feed adjusted 95 to a known operating condition, it is practical not only to deposit the adhesive uniformly on either all or selected parts of a length of web in its travel; but also, for subsequent repeat orders, similarly to deposit the adhesive on other webs, corresponding in thickness of deposit to the condition of earlier-treated webs. To this end, the distributing crosshead 10 is connected at its upper side with preferably branched 100 conduit members 20 connected at their tops with a union 21 which, at its top, is connected with a conduit 22 dependent from the bottom of a main and cylindrical upstanding container 23 for the adhesive or glue, 105 this container being supported on the top of an upstanding frame member 24 above and over the distributing crosshead, the container 23 holding the supply of adhesive for the distributing crosshead. The branched 110 conduit members 20 as shown are three in number, the outermost members severally connecting with the distributing crosshead near an end thereof and the intermediate branch member connecting with the distributing crosshead midway between its ends. 115 In this way close uniformity of supply of adhesive to the chamber of the transverse distributing crosshead is obtainable. The upstanding main cylindrical container 23 is 120 open at its top and provided with a piston 25 descent of which forces adhesive into the distributing crosshead through said conduits. The piston is provided with an upstanding threaded piston-rod 26, the lower 125

end of which is fixed to the piston which, by the present construction, is given a rotary movement whenever it is moved downwardly or upwardly in the container 23. 5 The threaded piston rod extends upwardly through a nut portion 27 of a top bracket 28 having dependent arms 29 which opposingly embrace the upper end of the container 23, the latter being detachably secured 10 to the bracket arms by set-screws 30. This bracket 28 has an upwardly-extending arm 31 provided with a horizontal lug 32 through which bolts 33 pass into the ceiling of the room of installation; but the bracket may 15 be, if desired, otherwise rigidly installed. Above the bracket 28, the threaded piston rod 26 extends upwardly through the hub 34 of a beveled gear 35, the hub bore being provided with an interiorly-projecting 20 feather 36 which is entrant in a groove 37 formed lengthwise of the piston rod 26. Rotation of the beveled gear 35 in one direction compels rotational descent, and in the other compels rotational ascent of the piston 25 in the cylindrical container 23. A beveled gear 38 in constant mesh with the beveled gear 35 constitutes the driving gear for the beveled gear 35, and also constitutes a piston-actuating gear. This beveled gear 38 is 30 fixed on the shaft 39 of an under cone pulley 40, the shaft being journaled in the upwardly-extending arm 31 and also in a hanger 41 fixed to the ceiling in parallelism to the arm 31. Above the shaft 39 there is 35 an upper and therewith-parallel shaft 42 similarly journaled in the arm 31 and hanger 41, and provided with a cone pulley 43, these two cone pulleys and their encircling edgewise-shiftable belt 44 forming a 40 well-known kind of change-speed mechanism. By adjustment of the belt 44 in a well-known way the intermeshed beveled gears 38 and 35 may have a variable driving speed given to them for the purpose of varying the speed of the descent of the piston 25 in the container. It will be noted that the beveled gear 35 is of considerably larger diameter than the beveled gear 38, and consequently, owing to such relations of the two 45 50 beveled gears one to the other, they together constitute a speed-reduction mechanism. The upper cone pulley shaft 42 is provided with a pulley 45 outwardly of the hanger 41, the pulley 45 having a friction peripheral surface 46. A pair of hangers 47 dependent from the ceiling and spaced laterally apart one behind the other, and in a direction corresponding to the front and rear position of the under part of the 55 machine, have their under ends connected by a horizontal, forwardly and rearwardly extending quadrangular bearing-block guide-frame 48. A journal or bearing-block indicated by 49 is slidably mounted in this 60 65 guide-frame and is at its rear side connected with the necked inner end of a horizontal rearwardly-extending bearing-block adjusting-spindle 50, the rearward end-portion of which is slidably mounted through an opening at 51 in the rearward vertical wall of 70 said frame 48 so that this bearing-block may be adjusted back and forth relatively to the friction pulley 45. Said bearing-block carries a transverse driven shaft 52 which projects from each end of the bearing-block 75 and which at its inward end is provided with an elliptical cam 53, the larger end of the cam being fixed to this end of the driven shaft 52. The other or outward end of the shaft 52 has a belt pulley 54 fixed to it, 80 and from this pulley a driving belt 55 extends to it over a rearward pulley 56 on the line driving shafting 57 which, adjacent to the pulley 56 is supported by a line-shafting hanger 58, and adjacent the pulley 56, outwardly of it, the driving shaft 57 is provided with a stepped pulley 59 from which a belt B extends downwardly over a stepped pulley 11 on the main shaft M. Stepped pulleys are preferably used together with 85 belt-shifting mechanism, not shown, for belt B in order to drive the main shaft M at various selected speeds from the line shafting. The rearmost hanger 47 has pivoted to it at 61 a lever 62 carrying a belt-tackling 90 pulley 63 which rests on the upper run of the belt 55 between the pulleys 54 and 56, the lower and downwardly-inclined end of the lever 62 being provided with an adjustable weight 64. The belt B is to be mounted 95 100 105 110 115 120 125 130 on its pulleys in order to keep the cams 53 and 72 in synchronous relations.

The main shaft M is provided with a beveled gear 65 inwardly of its stepped pulley 60, and this beveled gear is in constant mesh with a beveled gear 66 on the foot of an up-standing shaft 67 journaled in a vertical sleeve of a frame bracket 68 which is secured at 69 to the machine frame. The upper end of the shaft 67 is provided with a beveled gear 70 which is in constant mesh with a beveled gear 71 which together with an elliptical cam 72 is fixed on a short transverse shaft 73 having a bearing in a horizontal member 74 of the bracket 68 which is also shown as having a dependent arm 68^a, the foot of which is provided with a tubular bearing 68^b through which the main shaft M passes inwardly of the beveled gear 65. Each side of the machine frame has attached, as shown, directly to the outward legs 1, one of the brackets 68 and the elliptical cam, and its driving mechanism already described in connection with the right-hand end of the machine, is repeated at the left-hand end, the main shaft M at the left-hand end also being provided with a beveled gear 65. The outer end of each rod valve 17 is provided with a cam-engaging roll 17^a, and 130

each cam rod is provided outwardly of the distributing crosshead with an upstanding bearing support 75 secured to the machine frame and located adjacent an outward end 5 of the top surface of the machine frame, each elliptical valve 72 being in constant engagement with a cam roll 17^a, and each rod-valve outwardly of the distributing crosshead or distributor and between the end of 10 the distributor and the support 75, having a fixed collar 76 the inward face of which forms an abutment for a coil spring 77 which encircles the rod-valve and has its inward end in abutment against a stuffing 15 box 18 on an end of the distributor 10. The result is that as the elliptical cams rotate, the springs 77 press each rod valve outwardly against the periphery of an elliptical valve, thus effecting the separation of the 20 inward ends of the rod-valves and gradually opening the fluid exit in the bottom of the distributor according to the peripheral contour of the elliptical valve for outflow on the surface of the web W carried by and fed 25 over the roll 4 in the rearward direction by the pull of the pneumatic drum or feeding device 8.

For the reason that it is desired to keep the glue or other fluid with which the distributor is supplied under more or less pressure, and for the reason that such pressure causes an objectionable jetting out of the adhesive or other fluid through the exit of the distributor, especially when the rod-valves 30 are initially separated, to the detriment of the evenness and desired character of the deposit on the web, provision is made whereby the operator can at will not only during such initial separation of the rod-valves, but also 35 at any other time when it may become desirable to do so, arrest the rotation of the threaded piston rod 37 by throwing the elliptical friction driving cam 53 out of working contact with the friction pulley 46; and 40 this is readily accomplished by a movement of the accessible handle 78 of the hand lever 79 which is shown pivoted at 80 to an arm 81 from the hanger 47, and provided with an upper arm 82, the upper end of which is loosely 45 jointed at 83 to the outward end of the spindle 50 connected with the sliding journal box 49. This lever may be moved in either direction 50 to move the journal box 49 forwardly or rearwardly and thereby to adjust the cam 55 53 into or out of working position with the friction pulley 46 by rotation of which by means described, the piston rod is rotated. At all times during such adjustments the weighted lever 62 moves automatically with 60 its belt-engaging roll 63 in continuous contact with the upper run of the belt 55, and the slidable bearing-block 49 is kept normally pressed forward to keep the periphery of the elliptical cam 53 in working contact

with the friction pulley 46 by means of a 65 coil spring 84 around the spindle 50 between the rear side of the bearing-block and a collar 85 on the spindle.

The frame 24 is shown provided with a catch lug 85^a, the lever 79 being provided 70 with a catch 86 for engagement of the catch lug 85^a whereby the lever 79 may be held in the desired position with the cam 53 either in or out of contact with the friction wheel 46. 75

In the present case it would be necessary to reverse the direction of rotation of the line shafting, which is not to be desired, in order to reverse the direction of rotation of the intermeshing gears 38 and 35 from which the threaded piston rod 26 is screwed down through the internally threaded nut 27 with which the threads of the piston rod are in constant engagement; rotation of the gear 35 and of the feather 36 working in the 80 piston rod slot 37 compelling downward rotation of the threaded piston rod through its nut, and the walls of the lengthwise-extending groove 37 of the piston rod being in slidable engagement with that portion of 90 the feather projecting into the groove 37. Consequently in order to reverse the direction of rotation of the piston rod 26 for lifting the piston from its lowest position to an upper position or entirely above the 95 top of the container 23, I provide the shaft 39 with a square projection 87 for application of a hand crank by means of which when the cam 53 is out of contact with the friction wheel 46 the shaft 39 may be 100 readily turned in the appropriate direction to lift the piston 25.

In Fig. 9 a plurality of deposits y are shown on the web W, the deposits being separated one from another or spaced apart 105 at z. The separation of the disks is of course effected by the contour of the cams 72 and the coöperation of the cam surface contours with the rod-valves and springs 77. The contour of the valves 72 is also such 110 as to effect a gradual separating movement as the web is fed rearwardly, this separating movement continuing until the transverse diametrical line of the disk to be formed is reached when the coating cams 115 72, valve rod 17 and springs 77 cause a gradual approach of the free ends of the cam rods at the completion of a given disk. A considerable variety of different shapes of deposit may be effected during the continuous rearward travel of the web or backing during its feed movement, according to 120 the configuration of the peripheries of the cams 72. If abrasive material is to be made, the abrasive is deposited on the adhesive deposits on the web from the sander S, but when disks are to be made the transverse spreader 6 is to be removed in order to pre- 125

vent spreading of the adhesive disks. By removing the cams 72 and pulling the rod-valves outwardly into a movable position according to the width of the web, the slit 5 16 will be opened sufficiently to permit the deposit of the adhesive continuously across the full width of the upper surface of the web.

Obviously the machine may be used for 10 various other purposes than the deposit of adhesive and the formation of abrasive material. Any desired liquid may be distributed on the web. So also various kinds of material other than abrasive may be deposited on the web from the sander S. A striking advantage of the present machine is that the operator can instantly arrest the descent and consequently the pressure of the piston 25 on the contained liquid, and thereby 15 prevent spouting or jetting out of the liquid at the initial opening of the rod valve and at other times when necessary. Uniformity of deposit is always of importance, but it is of very great and particular importance in the manufacture of sandpaper and other sheet abrasive material, for reasons more fully set forth in my companion application Serial No. 341,470, filed November 29, 1919, and also in my method application Serial No. 341,472, filed November 29, 1919.

What I claim is,—

1. The combination of a revoluble web-support; a liquid-distributer having an exit 35 opposed to said support; a pair of aligned reciprocating rod-valves for said exit; a driven shaft operatively connected with the revoluble web-support; for each rod-valve, a cam for moving the rod valve in one direction, and a spring for moving the rod valve in the other direction; and means for operatively connecting each such cam with the driven shaft for giving simultaneous endwise movements to the rod valves and web-feeding mechanism.

2. The combination of a revoluble web-support; a liquid-distributer having an exit opposed to said support; a valve for said exit; a driven shaft operatively connected 50 with the revoluble web-support for rotating the latter; a valve-actuating device operatively connected with the driven shaft; a web mechanism; a driving shaft; means operatively connecting the driving shaft with the driven shaft; a change-speed mechanism provided with a driving gear; means for operatively connecting the change-speed mechanism with the driven shaft; a vertically-movable revoluble piston-rod; mechanism for operatively connecting the piston rod with the driving gear of the change-speed mechanism; a liquid-container provided 55 with a piston from which the piston rod extends, the container communicating with the distributer; a web-feeding mechanism; and means under the control of the operator for arresting the descent of the piston at will.

mechanism located rearwardly of the web-support.

3. The combination of a revoluble web-support; a liquid-distributer having an exit opposed to said support; a valve for said exit; a driven shaft operatively connected with the revoluble web-support for rotating the latter; a valve-actuating device operatively connected with the driven shaft; a web-feeding mechanism; a driving shaft; means operatively connecting the driving shaft with the driven shaft; a change-speed mechanism provided with a driving gear; means for operatively connecting the change-speed mechanism with the driven shaft; a vertically-movable revoluble piston-rod; mechanism for operatively connecting the piston rod with the driving gear of the change-speed mechanism; a liquid-container provided with a piston from which the piston rod extends, the container communicating with the distributer; a web-feeding mechanism; and means under the control of the operator for arresting the movement of the piston at will.

4. The combination of a revoluble web-support; a liquid-distributer having an exit opposed to said support; a pair of aligned reciprocating rod-valves for said exit; a driven shaft operatively connected with the revoluble web-support; for each rod-valve, a cam for moving the rod valve in the other direction; means for operatively connecting each such cam with the driven shaft for giving simultaneous endwise movements to the rod valves and web-feeding mechanism; a driving shaft; means for operatively connecting it with the driven shaft; a change-speed mechanism provided with a driving gear; means for operatively connecting the change-speed mechanism with the driven shaft; a vertically-movable revoluble piston-rod; mechanism for operatively connecting it with the driving gear of the change-speed mechanism; a liquid container provided with a piston from which the piston rod extends, the container communicating with the distributer; a web-feeding mechanism; and means under the control of the operator for arresting the descent of the piston at will.

5. The combination of a revoluble web-supporting roll; apparatus provided with an exit for forcing a fluid through the exit under artificial pressure on the liquid in the container; means for creating such pressure; a disk-forming valvular mechanism for said exit; means for operating such valvular disk-forming mechanism; and means under the control of the operator for relieving said pressure at will, said means comprising a friction wheel and a therewith-disconnectible cam for driving said friction wheel.

6. In a machine of the class specified, the combination of a liquid container having an

exit; a revoluble and endwise-moving piston for said container; a piston rod for the piston; mechanism for rotating the piston rod; means to compel its descent during its 5 rotation; and for coöperation with the mechanism for rotating the piston rod, a cam mounted in a sliding journal box; said slid-

ing journal box; and means under the control of the operator for moving said journal box to carry the cam into and out of 10 operative position.

In testimony whereof I have hereunto set my hand this 28th day of November, 1919.

HERMAN BEHR.
